UNITED STATES PATENT OFFICE.

JOSEPH LEDWINKA, OF PHILADELPHIA, PENNSYLVANIA, ASSIGNOR, BY MESNE ASSIGNMENTS, TO BUDD WHEEL COMPANY, OF PHILADELPHIA, PENNSYLVANIA, A CORPORATION OF PENNSYLVANIA.

PROCESS OF MAKING PRESSED-STEEL WHEELS.

Original application filed February 21, 1917, Serial No. 150,084. Divided and this application filed August 16, 1921. Serial No. 492,767.

To all whom it may concern:

Be it known that I, JOSEPH LEDWINKA, a citizen of the United States, residing at Philadelphia, Pennsylvania, have invented 5 certain new and useful Improvements in Processes of Making Pressed-Steel Wheels, of which I declare the following to be a full, clear, and exact description.

This invention relates to an improved 10 process of making pressed steel wheels. The subject matter of this application is divided from my application for pressed steel wheels and the process of making the same, Serial No. 150,084, filed February 21st, 15 1917, on which Letters Patent, No. 1,423,229 were granted, July 18, 1922.

The object of my invention is to provide an improved process of making pressed steel wheels by means of which the hub and 20 spokes may be formed from a single blank of sheet metal with a minimum amount of waste.

Further objects, and objects relating to 25 details and economies of operation, will definitely appear from the detailed description to follow. My invention is clearly defined and pointed out in the appended claims. One embodiment of my invention is illustrated in the accompanying drawing, forming a part of this specification, in 30 which:

Fig. 1 is a side elevation of a pressed steel wheel constructed in accordance with my invention, parts being broken away and 35 parts in section.

Fig. 2 is a transverse, sectional view, taken on the line 2—2 of Fig. 1.

Fig. 3 is a detail view of a form of split 40 ring used to retain the wheel in place on the hub.

Fig. 4 is a broken, sectional view through the retaining ring and hub cap.

Fig. 5 is a detail view showing a form of rim employed in connection with my invention.

Fig. 6 is a similar view showing the connection of the spokes to the rim.

Fig. 7 is a view of a steel sheet which has been blanked out ready to be formed into a 50 wheel in accordance with my invention, and

Fig. 8 is a section on the line 8—8 of Fig. 1.

In the drawings, the same reference numerals refer to the same parts throughout the several views, and the sectional views are 55 taken looking in the direction of the arrows at the ends of the section lines.

In carrying out my invention, a steel sheet or plate is first stamped or blanked into the form shown in Fig. 7, that is, the blank is 60 formed with a central solid portion, 10, the ends, 11 and 12, of which are tapered or inclined relative to the longitudinal axis of the body portion. Each side portion of the blank is kerfed or slotted, as shown at 13, 65 to form spoke portions, 14. These spoke portions are arranged in staggered relation so that the spoke portions on one side of the central body portion are out of line with those on the other side of the central body 70 portion. The kerfs or slots, 13, may be shaped so as to provide the spoke portions, 14, with the enlarged ends, 15. In forming the blank, the spoke portions may be pressed into the transversely curved shape shown 75 in Fig. 8, at 16, so as to strengthen the spokes and improve the appearance of the wheel.

After the blank has been formed, it is 80 rolled into a tube and the tapered or inclined edges, 11 and 12, are secured together by welding or otherwise. The tube thus formed is expanded in suitable shaping dies at the end portions of the tubular portion formed by the body, 10, of the blank. This 85 tubular portion forms the wheel body or central sleeve which receives the inner hub on which the wheel is supported. The inner end of this tubular portion is expanded to a greater extent than the outer, giving this central sleeve a longitudinal taper, at 17, to facilitate the mounting of the wheel on the inner hub. This enlarged end, 17, may be pressed into polygonal shape in cross-section, as indicated at 19, Fig. 1, to cooperate with a 90 correspondingly shaped part of the inner hub. This forms a simple driving connection between the wheel and the inner hub. A reinforcing ring, 20, may be applied to the enlarged end, 17, if desired.

The spoke portions, 14, are bent outwardly 100 so as to bring the free ends of one set into line with the free ends of the other set and then secured to the wheel rim. Since the

spoke portions on one side of the blank are out of line with those on the other side of the blank, when they are bent outwardly the spokes will be staggered as appears from Fig. 1. I have illustrated a tire rim formed of complementary portions, 21 and 22, each having a tire-engaging flange, 23, along one edge and an offset flange, 24, along the other edge. In assembling the wheel, the flanges, 24, of the rim sections are brought together and the enlarged ends, 15, of the spokes are clamped between these flanges. The rim flanges, 24, and the spoke ends, 15, are then welded or otherwise secured together. In practice, I prefer to notch out the opposed surfaces of the flanges, 24, at the points where the spoke ends engage them, as indicated at 25, Fig. 5, but not to a sufficient extent to permit the opposed surfaces of the flanges, 24, to come into contact with each other when the spoke ends are seated in the notches, 25. This enables me to secure a most expeditious, effective and economical welding together of these parts under the influence of heat and pressure, thus producing a strong and durable, but inexpensive structure.

The wheel constructed in accordance with my process may be mounted on an inner hub, 26, carried by axle, 27, and provided with a seating portion, 28, shaped to conform to and receive the enlarged end, 17, of the wheel body. The outer end, 29, of the hub, 26, may be threaded externally to receive a hub cap, 30, by which the wheel is retained detachably on the inner hub. The hub cap, 30, has an annular shoulder, 32, and a tapered surface, 31, adjacent thereto. A split ring, 33, which may be stamped out of sheet metal, 40 is seated on the tapered surface, 31, and has a flange portion, 34, engaging the outer end of the wheel bore to clamp the wheel upon the hub. A brake drum, 35, may be secured to hub, 26, if desired.

45 The rim construction and the connection between rim and spokes, which is disclosed here, is described and claimed in Letters Patent, No. 1,371,382, pressed steel wheel, issued March 15th, 1921, on another division 50 of my said application, Serial No. 150,084. The means for retaining the wheel on the inner hub are described and claimed in Letters Patent, No. 1,442,621, issued January 16, 1923, on my application for retaining 55 devices for removable wheels, Serial No. 195,514, filed Oct. 9, 1917, which was another division of the said application, Serial No. 150,084.

60 I am aware that the particular embodiment of my invention disclosed in this application is susceptible of considerable variation without departing from the spirit of my invention, and, therefore, I claim my invention broadly, as indicated by the appended claims.

Having thus described my invention, what I claim as new and desire to secure by Letters Patent is:—

1. In the manufacture of pressed steel wheels, the process which comprises stamping out a sheet metal blank to form a central body portion and spoke portions on opposite sides of the body portion, rolling the stamped blank into the form of a tube, expanding the end of the bore of the tube 75 adjacent one edge of the body portion, and bending outwardly the spoke portions.

2. In the manufacture of pressed steel wheels, the process which comprises stamping out a sheet metal blank to form a central body portion and spoke portions on opposite sides of the body portion, with the spoke portions on one side out of line with those on the other side of the body portion, 80 rolling the blank into the form of a tube, 85 and bending the spoke portions outwardly.

3. In the manufacture of pressed steel wheels, the process which comprises stamping out a sheet metal blank to form a central body portion and spoke portions on 90 opposite sides of the body portion, rolling the blank into the form of a tube, bending the spoke portions outwardly, and securing the free ends of the spoke portions together.

4. In the manufacture of pressed steel wheels, the process which comprises stamping out a sheet metal blank to form a central body portion and spoke portions on opposite sides of the body portion, with the spoke portions on one side out of line 95 with those on the other side of the body portion, rolling the blank into the form of a tube, bending the spoke portions outwardly to bring their free ends into line with each other, and securing said free ends together. 105

5. In the manufacture of pressed steel wheels, the process which comprises stamping out a sheet metal blank to form a central body portion with inclined ends and spoke portions at the opposite side edges of the body portion, rolling the blank into the form of a tube and securing the said inclined ends together, and bending the spoke portions outwardly to bring their free ends 110 toward each other. 115

6. In the manufacture of pressed steel wheels, the process which comprises stamping out a sheet metal blank to form a central body portion and spoke portions on opposite sides of the body portion, rolling the blank into the form of a tube and securing the ends of said body portion together, expanding one end of said tube, bending the spoke portions outwardly, and securing the 125 free ends thereof to a tire rim.

7. The process of making wheels which consists in cutting from sheet metal a wheel member and integrally-attached spoke elements extending from opposite side edges 130

of said wheel member and separated by slits staggered with respect to the opposite slits, shaping the cut-out structure into the form which it occupies in the finished wheel 5 by bending said wheel member into circular form and by bending said spoke elements backwardly through more than 90° to cause the free end portions of said spoke elements at opposite ends of said wheel member to converge toward each other, and securing a 10 second wheel member to the free ends of said spoke elements.

In testimony whereof, I affix my signature,
JOSEPH LEDWINKA.
